Inventor,

Leo Shlick;

By A. B. Ellpham
Attorney.

UNITED STATES PATENT OFFICE.

LEO SHLICK, OF MONTREAL, QUEBEC, CANADA.

BEATING ENGINE.

Application filed February 17, 1921. Serial No. 445,736.

This invention relates to the art of paper making, and has for its object the effecting of certain improvements in beating engines for the production of paper-pulp, as follows:

First, it has for its purpose the provision of a variable discharge from the beater roll. Second, the improvement of the beater roll itself, and also of the bed-plate. Third, the effecting of means for withdrawing a substantial proportion of the water from the pulp on its way to the beater roll, and for delivering it beyond the same. Fourth, the reduction of the stock channel about the feather in order to increase the velocity of the circulation.

Fifth, the effecting of certain other improvements in detail of construction hereinafter set forth.

In the drawings forming part of this specification, Fig. 1 is a side section of a part of a beating engine. Fig. 2 is a cross section thereof. Fig. 3 is a cross section of a modified form of the engine. Fig. 4 is a side section of the same. Fig. 5 is a side sectional view of a modification of the engine. Fig. 6 is a plan view of the beater engine. Fig. 7 is a longitudinal section of the beater roll. Fig. 8 is an end view of a part of the roll.

In the beating engine embodying my improvements, the tub 1 is of substantially well-known construction, having a mid-feather 2, a beater roll 3 and bed-plate 4. For providing a variable discharge from the beater roll, the bed-plate is given an extension 5, and behind the upper edge of the latter descends the lower edge of a double plate 6, whose other edge passes behind a lip 7 rising from a back-fall board 9, the plate 6 comprising the back-fall, and the topmost portion thereof being the crest of the back-fall. This causes the pulp and water from the beater roll 3 to rise to a considerable height before descending to the back-fall board and discharging into the channel about the mid-feather. This bed-plate crest 6 is vertically adjusted by means of screw rods 10, and hand wheels 11 supported by a hood 12. The out-flowing stock is reduced to a lower discharge level by means of a vertical gate 13 adjustably supported by the beater hood, the lower edge of the gate 13 being below the level of the top of the back-fall. This

serves to materially increase the velocity of 55 the out-flow and thereby to decrease precipitation of the pulp in the channel.

The hood 12 is pivotally supported at 14 and angularly adjusted by means of a screw rod 15 and hand wheel 16, a deflector 17 depending therefrom close to the fly-bars 19 of the beater roll, in order to prevent any lumps of the fibre pulp from passing back over the roll. A stationary hood 20 60 envelopes the top of the beater roll and terminates in a discharge 21 for receiving and delivering the sufficiently treated pulp which is carried back up and over the roll, an angularly adjustable lip 22 aiding in the better reception of the pulp into the discharge 21. 65

In Figs. 3 and 4 is illustrated another means for varying the discharge over the back-fall. Here a deflector board 23 is supported midway between the hood 12 and the back-fall board 9, and adjusted both angularly and vertically by means of screw rods 24, 25 and hand wheels 26, 27 thereon. This serves substantially the same purpose as the adjustable back-fall 6. In place of the 70 75 slideable gate 13 shown in Fig. 1, a gate 29 hinged at 30 is provided. An arm 31 rigid with the hood 12 and projecting into contact with a cam surface 32 connected with the bearing of the beater roll 3, so that as the latter is raised and lowered, the hood 80 will rise and fall in unison therewith. 85

In Fig. 5, there is illustrated, in addition to a slightly different arrangement of the hood and of its adjusting means, a means 90 for separating from the pulp and water flowing toward the beater roll, a portion of the water and of the more fully treated pulp, and delivering it back of the back-fall. This, which is also shown in Fig. 6, consists of a wheel 33 rotatably supported in the tub and formed with cupped vanes 34 discharging into a tubular axle 38, whose open end is located over a basin 35 connected by a pipe 36 to an overhung mouth 37 in the back-fall. It is, of course, understood that there is a suitable opening at the inner end of each vane through the tubular axle 38 for the passage into the axle of the pulp caught up by the vanes 34. If it is found that too much of the pulp caught up by one vane flows directly downward through the hole of a following vane instead of along to 95 100 105

the outer end of the axle, the latter can be divided by axial partitions so that the pulp from each vane passes by itself along the axle to its end. A netting 39 encloses the 5 vanes 34 and thereby prevents any but the fluid portion of the pulp from being removed from in front of the beater roll and delivered back of the back fall. This aids in accelerating the flow of the pulp about 10 the mid-feather, by introducing the fluid between the stock and the surface of the channel. The separating wheel 33 is made to rotate by the flow of the pulp toward the beater roll.

15 To further increase the speed of flow, I prefer to narrow the channel between the ends of the mid-feather 2 and the ends of the tub, where the pulp is apt to settle and clog the flow. To do this, the ends of the mid- 20 feather are provided with rounded heads 40 slidably adjusted toward and from the ends of the tub, and held at any desired point of adjustment by bolts and nuts 41, 42.

I also prefer to narrow the channel just 25 in front of the beater roll, as at 43 in Fig. 6, in order that the current of pulp and water shall meet the beater roll and bed plate centrally thereof, and with greater velocity.

At one end of the tub is an emptying 30 opening 44 provided with a vertically slide- able gate 45, as shown in Figs. 5 and 6. By turning its screw rods 46 until the top edge of the gate has descended to a short distance above the floor of the tub, the con- 35 tents of the tub escape therefrom, leaving en- trapped by the gate 45 any trash, as nails, scraps of tin and the like.

When changing over from one special 40 product to another, it is often necessary to load the bearings of the beater roll, or their supports, so as to increase the pressure of the beater elements. This results in a distortion of the beater elements on account of the deflection of the shaft. I prefer to place 45 weights around the shaft of the roll, such weights 47 being composed of any suitable material, as concrete, lead and the like, and preferably circular and mounted on the shaft 49 between the roll-heads 50, the roll 50 being split longitudinally to permit their application and removal, as in Fig. 8.

The knives or fly-bars 19 are preferably 55 formed as parts of plates 52 which are adapted to be slid into dove-tail seats or grooves 53, as shown in Fig. 8, and to be held against longitudinal displacement by means of bolts 54 passing through ears 55, as shown in Figs. 7 and 8.

I prefer to bend the fly bars 19, as shown 60 in Fig. 6, so that the two halves of each compose an oblique angle with respect to each other, and so disposed that the central bends reach the bed plate before their ends and thereby facilitate the expulsion of the 65 entrained air from between the fly bars. By

thus forcing the air out from between the fly-bars, the stock can enter more freely and thereby receive a more perfect beating effect.

As shown in Fig. 5, the tub 1 is supported 70 near one end on a socket 56 and at its other end by an adjusting screw 57 in order to slightly tilt it and thereby to vary the flow of the stock therein:

In the arrangement of the hood 12 shown 75 in Fig. 5, the same is pivotally supported at 60 and at its other end provided with an arm 61 resting upon the bearing of the roll 3. I do not specifically claim the constructions illustrated by Figs. 3, 4, 5 and 6.

What I claim is:

1. A beating engine comprising a beater roll, coacting bed-plate and knives, a back-fall, a board rising from the bed-plate, a lip rising from said board, a folded plate having 85 its edges resting against said lip and board, and means for vertically adjusting said folded plate.

2. A beating engine comprising a beater roll, bed-plate, a back-fall board, two spaced 90 members rising from the back-fall board and bed-plate, respectively, a folded plate having its edges resting against said spaced members, and screw rods for vertically adjusting said folded plate.

3. A beating engine comprising a beater roll, bed-plate, a back-fall board, a vertically adjustable plate rising from the back-fall board, and a deflector gate depending into proximity to an upper portion of the beater roll, said plate and deflector being simultaneously adjustable vertically.

4. A beating engine comprising a beater roll, bed-plate, a back-fall board, a hood pivotally supported, means for its angular adjustment, a deflector depending from said hood into proximity to the beater roll, and a plate rising from the back-fall board and adjustably supported by said hood.

5. A beating engine comprising a tub, a beater roll, a back-fall, a hood located above 110 said back-fall, a gate depending from said hood below the level of the stock back of the beater roll, and means for vertically adjusting said hood.

6. A beating engine comprising a tub, a beater roll, a back-fall, a hood located above 115 said back-fall, and means for vertically adjusting said hood in relation to the beater roll.

7. A beating engine comprising a tub, a beater roll, a back-fall, a semi-cylindrical hood located above said back-fall, and means for raising and lowering said hood in relation to the beater roll.

8. A beating engine comprising a tub, a beater roll, a vertically adjustable back-fall, a hood located above said back-fall, and means for raising and lowering said hood 125 relative to said back-fall.

9. A beating engine comprising a tub, a beater roll, an adjustable back-fall, a hood located above said back-fall, a vertically adjustable gate depending from said hood close to the back surface of the beater roll, and means for raising and lowering said hood in relation to the beater roll. 5
10. A beating engine comprising a tub, a beater roll, a hood located above said beater roll, a back-fall, and means for its vertical adjustment embracing slots through the side walls of the tub, and trunnions reaching through said slots. 10
11. A beating engine comprising a tub, a beater roll, a back-fall having its topmost point above the horizontal center line of the beater roll, and means for vertically adjusting said back-fall embracing slots through the side walls of the tub, trunnions 15 reaching through said slots and elevating mechanism connected with the outer ends of said trunnions. 20
12. A beating engine comprising a tub, a beater roll, a back-fall, and means for vertically adjusting said back-fall embracing slots through the side walls of the tub, trunnions extending through said slots, screw rods engaging the upper of said trunnions, and nuts turning on said screw rods. 25
13. A beating engine comprising a tub, a beater roll, a back fall, and means for vertically adjusting said back-fall embracing slots through the side walls of said tub, trunnions reaching through said slots, a screw rod at each side of said tub engaging one of said trunnions, a nut on each screw rod, bevel gears and a cross shaft for causing said nuts to turn simultaneously. 30
14. A beating engine comprising a tub, a beater roll, a back-fall, and means for vertically adjusting said back-fall embracing slots through the side walls of said tub, trunnions reaching through said slots, means engaging the outer ends of said trunnions 40 for simultaneously adjusting both sides of the back-fall, a plate within each side wall covering the slot therethrough, and resilient means pressing said plates against the inner surfaces of the tub. 45
15. A beating engine comprising a tub, a beater roll, a back-fall, and means for its vertical adjustment embracing slots through the side walls of said tub, trunnions reaching through said slots, sleeves slidable on 50 said trunnions, plates covering the inner surfaces of said side walls about said slots, helical springs mounted on said sleeves to press said plates against said inner surfaces. 55
16. A beating engine comprising a tub, a beater roll, a back-fall and means for its vertical adjustment embracing slots through the side walls of said tub, two vertically spaced trunnions at each side of said back-fall extending through the slot thereat, plates covering said slots within said tub, 60
- and resilient means pressing said plates against the surfaces of the side walls, said trunnions passing through said plates. 65
17. A beating engine comprising a tub, a beater roll, a back-fall, and means for the vertical adjustment of said back-fall comprising slots through the side walls of said tub, operative mechanism reaching through said slots, and means for sealing said slots to prevent leakage of stock through them. 70
18. A beating engine comprising a tub, a beater roll, a back-fall, a hood located above said back-fall, and means for horizontally adjusting said hood to present its rear nearer to or farther from the back surface of the roll. 75
19. A beating engine comprising a tub, a beater roll, a back-fall, a hood located above said back-fall, a deflector gate depending from said hood close to the back surface of said roll, and means for horizontally shifting said gate to adjust the clearance between it and said roll. 80
20. In a beating engine, a beater roll comprising a drum having longitudinally disposed dovetail slots in its periphery, and segments having dovetail portions fitting said slots, each segment having several fly-bars integral therewith and an inwardly projecting lug adapted to be fastened to an end of the drum. 85
21. A beating engine comprising a tub, a beater roll, a bed-plate, a back-fall, a hood located above the back-fall, a deflector depending close to the surface of the roll, an inclined member spaced above the back of the back-fall, and a vertically adjustable gate depending from said hood to a level below that of the crest of the back-fall. 90
22. A beating engine comprising a tub, a beater roll, a bed-plate, a back-fall, a hood located above the back-fall, an inclined floor member spaced over the back of the back-fall, and a vertically adjustable gate depending from said hood to a level below that of the crest of the back-fall, said inclined floor member reaching beyond said gate. 100
23. A beating engine comprising a tub, a beater roll, a bed-plate, a back-fall and a hood located above the back-fall, the inner surface of the hood being extended rearward and downward to a level below that of the crest of the back-fall. 110
24. A beating engine comprising a beater roll, tub, bed-plate, backfall rising above the level of the axis of the roll, and deflecting curb located above the backfall, the face of the backfall adjacent the roll being flat from the point where it leaves the bed-plate to its upper edge, and inclined at an angle of twenty degrees from the vertical, whereby the stock from the roll is thrown upward to the deflecting curb and clear of the back-fall. 115
25. A beater roll having longitudinal dove- 120
- 125
- 130

- tail grooves in its periphery, and plates bearing the fly bars, provided with projections fitting said grooves, each plate having a lug at one end extended toward the axis of the roll, and a bolt for each lug, for fastening said plates against longitudinal displacement.
26. A beater roll having a shaft, and weights adapted for application upon the shaft within the roll.
27. A beating engine comprising a tub, a beater roll, a bed-plate, a back-fall, a hood located above the back-fall, and a vertically adjustable gate depending from said hood to a point considerably below the level of the topmost portion of the back-fall.
28. A beating engine comprising a tub, a beater roll, a bed-plate, a back-fall, a hood located over the back-fall, and a gate supported above the back-fall, the upper end of the back fall being above the level of the axis of said roll, and the lower edge of said gate being below such level, and the back-fall being extended to a point beyond the plane of said gate, whereby a head is given to the pulp discharging from the back-fall which greatly increases the speed of the pulp-circulation.
29. A beating engine comprising a tub, a beater roll, a bed-plate, a back-fall having its crest above the level of the axis of the beater roll, a hood located over the back-fall, and a gate fixed in a vertical position spaced above the back-fall, the lower edge of the said gate being considerably below the level of the highest part of the back-fall.
30. A beating engine comprising a beater tub, a beater roll, a back-fall having its crest above the level of the axis of said roll, the intake level ahead of the roll being lower than the crest of the back-fall, and means for obstructing the flow of the stock from the back-fall descending to a point considerably below the level of the crest of the back-fall, whereby to increase the head and the flow of the stock beyond said point.
31. A beating engine comprising a beater tub, a beater roll, a back-fall having its crest above the level of the axis of said roll, and a gate located in the channel of said tub having its lower edge considerably below the level of the crest of the back-fall.
32. A beating engine comprising a beater tub, a beater roll, a back-fall having an elevated crest, and a gate located in the channel of said tub having its lower portion below the level of said crest and rounded to present a convex surface to the flow of the stock past it.
33. A beating engine comprising a beater tub, a beater roll, a back-fall having an elevated crest, and a gate located in the channel of said tub having its lower portion considerably below the level of said crest and vertically adjustable.
34. A beating engine comprising a tub, a beater roll, a back-fall, a hood located above the back-fall, and means for depressing the surface of the stock above the foot of said back-fall very considerably, whereby to constrict the area of the tub in order to build up a considerable head between said back-fall and the constricting area.
35. A beating engine comprising a tub, a beater roll, a back-fall, and a vertically disposed gate depending into the stock behind said back-fall, the lower edge of said gate being considerably below the level of the axis of the beater roll, whereby to build up a considerable head back of the back-fall between the latter and said gate.
36. A beating engine comprising a tub, a beater roll, a back-fall and a vertically disposed gate depending into the stock behind said back-fall, the lower edge of said vertical gate being considerably below the topmost point of said back-fall, whereby to build up a head between said back-fall and gate.
37. A beating engine comprising a tub, a beater roll, a back-fall, a vertically disposed gate depending into the stock back of the back-fall, and means for fastening said gate to the walls of the tub.
38. A beating engine comprising a tub, a beater roll, a back-fall, and a vertical gate depending into the stock back of the back-fall, the lower portion of said gate as it presents itself to the onflowing stock being curved to offer a minimum of resistance to the passage of the stock.

In testimony that I claim the foregoing invention, I have hereunto set my hand this 15th day of February, 1921.

LEO SHLICK.
